ABSTRACT

In a cathode ray tube of the type in which a plurality of electron beams are directed toward a phosphor screen by a beam generating assembly and are made to intersect each other substantially at the optical center of a main focusing electron lens by which all of the beams are focused on the screen, the usual grid electrode assembly is provided with an additional or auxiliary electrode for at least one of the beams, which auxiliary electrode has applied thereto a selected voltage by which the beam cutoff voltages for the plural beams can be maintained at selected values while permitting independent control of the modulation conditions for the several beams.

CATHODE RAY TUBE

This invention relates generally to cathode ray tubes of the single-gun, plural-beam type, and more particularly to improvements in cathode ray tubes of that type in which the plurality of electron beams are passed substantially through the optical center of a common electron lens by which all of the beams are focused on the color phosphor screen.

In single-gun, plural-beam cathode ray tubes of the type to which this invention relates, for example, as disclosed in detail in the U.S. Pat. No. 3,448,316, issued June 3, 1969, and having a common assignee herewith, a plurality of electron beams are originated by a beam generating cathode assembly comprising, for example, a plurality of cathodes, and are converged to intersect each other substantially at the optical center of a single main electron lens by which the beams are focused on the color screen, thereby to diminish optical aberrations imparted to the beams in the course of the focusing thereof by the main electron lens.

Converging of the beams to intersect each other substantially at the optical center of the main electron lens and simultaneous pre-focusing of the beams are effected by an auxiliary electron lens or the like which is common to all of the beams and located between the cathode assembly and the main electron focusing lens. When the beams are converged to intersect each other substantially at the optical center of the main electron lens, at least certain of the beams emerge from the lens along divergent paths, and pairs of convergence deflecting plates may be arranged along such divergent paths and have voltages applied therebetween to deflect the beams in directions for causing all of the beams to converge at a common point on an apertured beam selecting grill or mask placed adjacent the color screen so as to produce color pictures on the screen. Further, the beams are simultaneously deflected by the magnetic fields resulting from the horizontal and vertical sweep signals applied to corresponding coils of a deflection yoke to cause the beams to scan the screen.

In such single-gun, plural-beam cathode ray tubes in which the electron beams are simultaneously emitted from the cathodes, dispersion is introduced in the modulation characteristics of the beams by voltage variations in the video input signals applied to the cathodes or grids, or therebetween, as is the case with usual plural-gun cathode ray tubes employing three electron guns, and it is necessary to make the modulation characteristics of the beams uniform so as to provide pictures with good quality. To this end, it has been preferred that a second grid of the gun be divided into individual second grids each corresponding to a respective cathode of the electron gun emitting a corresponding electron beam. However, in the electron gun of the type in which the plural beams are pre-focused by a common auxiliary electron lens, the second grid plays an important role in forming a potential distribution which is symmetrical with respect to the axis of the gun and which constitutes the common auxiliary electron lens. Accordingly, from the viewpoint of avoidance of distortion of the electric field of the auxiliary electron lens, it is undesirable to divide the second grid into individual second grids to which different voltages are applied. Further, the provision of the independent second grids for the plural beams introduces complexity in the construction of the electron gun.

Accordingly, it is an object of this invention to provide an improved cathode ray tube of the aforementioned type which provides a picture of high quality on the screen.

More specifically, it is an object of this invention to provide an improved cathode ray tube of the aforementioned type in which the beam modulation conditions for the several beams may be controlled independently of each other.

It is still another object of this invention to provide an improved cathode ray tube of the aforementioned type which is suitable for use in large size tubes.

In accordance with an aspect of this invention, a cathode ray tube of the single-gun, plural-beam type is provided with a grid electrode assembly having auxiliary electrodes to which desired potentials are applied. Since the beam cutoff voltage

and beam modulating condition are dependent upon the potential difference between the first grid electrode and the auxiliary electrode, they can be changed by controlling the potential applied to the auxiliary electrode. Accordingly, the beam cutoff voltages for the respective beams can be adjusted to a common desired value by supplying the auxiliary electrodes with selected potentials and the beam modulation condition for each beam may be controlled independently of the others without causing distortion in the electron lens by which the beams are converged and/or prefocused.

The above, and other objects, features and advantages of this invention, will become apparent from the following description of illustrative embodiments which is to be read in conjunction with the accompanying drawings, wherein:

15 FIG. 1 is a schematic view showing a prior art single-gun plural-beam cathode ray tube of the type to which this invention may be applied;

20 FIG. 2 is a schematic cross-sectional view illustrating the principal part of a plural-beam electron gun and showing one embodiment of this invention incorporated therein;

FIGS. 3, 4 and 5 are views similar to that of FIG. 2, but showing other embodiments of the invention;

25 FIGS. 6A and 6B and FIGS. 7A and 7B are schematic detail views to which reference will be made in explaining the invention; and

FIGS. 8 and 9 are schematic views similar to that of FIG. 2, but showing further modified forms of this invention.

For a better understanding of this invention, a description 30 will be given of the type of plural-beam electron gun to which this invention is applied, and which is shown in FIG. 1. The reference character A indicates generally the electron gun, in which three cathodes K_R , K_G and K_B are aligned, for example, in a horizontal direction. The gun A further includes a first

35 cup-shaped common grid G_1 , a second cup-shaped common grid G_2 and third, fourth and fifth tubular grids G_3 , G_4 and G_5 sequentially arranged coaxial with the center cathode K_G . The first grid G_1 has apertures g_{1R} , g_{1G} and g_{1B} formed therein in alignment with the cathodes K_R , K_G and K_B and the second

40 grid G_2 has apertures g_{2R} , g_{2G} and g_{2B} formed therein in alignment with those of the first grid G_1 . A voltage of 0-400 V. is applied to the first grid G_1 , a voltage of 0 to 500 V. is applied to the second grid G_2 , a voltage of 13 to 20 KV. is applied to the third and fifth grids G_3 and G_5 and a voltage of 0 to 400 V.

45 is applied to the fourth grid G_4 . With such voltage distribution, an auxiliary electron lens L' is formed between the second and third grids G_2 and G_3 and a main electron lens L is formed by the third, fourth and fifth grids G_3 , G_4 and G_5 approximately at the axial center of the fourth grid G_4 . The auxiliary lens L' 50 prefocuses the three beams B_R , B_G and B_B emitted from the cathodes K_R , K_G and K_B and causes the side beams B_R and B_B to converge so that they cross or intersect with the center beam B_G substantially at the optical center of the main lens L and diverge therefrom. An electrostatic convergence deflecting

55 means C is provided to deflect the side beams B_R and B_B . The convergence deflecting means C comprises, for example, a pair of opposed shielding plates P and P' permitting the passage therebetween of the center beam B_G and deflector plates Q and Q' respectively disposed in opposed relationship to the shielding plates P and P' for convergently deflecting the side beams B_R and B_B toward the center beam B_G . The shielding plates P and P' are supplied with, for example, an anode voltage V_P of the cathode ray tube which may be the same as the voltage of the fifth grid G_5 so that the center beam B_G passes undeflected between the plates P and P' and impinges on a color screen S. The deflector plates Q and Q' are supplied with a convergence voltage V_Q which is lower than the anode voltage V_P by about 200 to 300 V., so that the beams B_R and B_B 65 passing between the plates Q and Q' are deflected in the manner of an optical prism to be converged on the screen S together with the beam B_G . In this manner, the three beams B_R , B_G and B_B passing through the convergence deflecting means C impinge on the screen S. The screen S is made up of,

60

70 for example, red, green and blue phosphor strips S_R , S_G and S_B

65

75

sequentially arranged, for instance, vertically in a repeating cyclic order. Adjacent the screen S there is provided a beam selecting grid G_p consisting of grids or slits g_p , each placed in front of a corresponding array or triplet of the red, green and blue phosphor strips S_R , S_G and S_B . The beam selecting electrode G_p is supplied with a high voltage V_p , by which the three beams B_R , B_G and B_B are directed between adjacent grids at predetermined incidence angles to land on the red, green and blue phosphor strips S_R , S_G and S_B . Reference character D designates the electromagnetic deflecting means for deflecting the beams horizontally and vertically so as to scan the screen.

Referring now to FIG. 2, which shows one example of the plural-beam electron gun with an embodiment of this invention incorporated therein, it will be seen that those elements corresponding to the gun of FIG. 1 are identified by the same reference characters and will not be further described.

In accordance with the present invention, auxiliary electrodes G'_{2R} , G'_{2G} and G'_{2B} for adjusting cathode cutoff voltages are interposed between the first and second grids G_1 and G_2 to respectively influence the beams emitted from the cathodes K_R , K_G and K_B . The auxiliary electrodes G'_{2R} , G'_{2G} and G'_{2B} are supplied with positive potentials V_1 , V_2 and V_3 relative to the cathodes K_R , K_G and K_B , have formed therein apertures g'_{2R} , g'_{2G} and g'_{2B} in alignment with the cathodes K_R , K_G and K_B .

With such an arrangement, the cutoff voltages of the beams B_R , B_G and B_B are dependent upon the potential relationship among the cathodes K_R , K_G and K_B , the first grid G_1 and the auxiliary electrodes G'_{2R} , G'_{2G} and G'_{2B} . Accordingly, by suitably selecting the potentials V_1 , V_2 and V_3 of the auxiliary electrodes G'_{2R} , G'_{2G} and G'_{2B} , the beam cutoff voltages can be made equal to one another without asymmetrical distortion of the electric field of the auxiliary lens L' formed by the second grid G_2 . At the same time, the bias voltage levels of the cathodes K_R , K_G and K_B can be made equal to one another, thereby to provide for uniform modulation characteristics of the respective beams.

The shape of the second grid G_2 greatly affects the formation of the auxiliary lens without distortion but its potential V_{g2} has little influence on the prefocusing of the beams, so that at least one of the auxiliary electrodes, for example, the auxiliary electrode G'_{2G} , may be at the same potential as the second grid G_2 . Thus, it is possible to connect the central auxiliary electrode G'_{2G} with the second grid G_2 in advance so as to eliminate the need for external terminals connected with such auxiliary electrode.

In the event that the second grid G_2 and, for example, the central auxiliary electrode G'_{2G} are maintained at the same potential, it is possible to omit the central auxiliary electrode and to shape the second grid G_2 to perform the function of the omitted auxiliary electrode for the central beam B_G , as shown in FIG. 3. In this case, that portion of the second grid G_2 facing the central cathode K_G projects outwardly, as at G'_{2G} , and the projecting end face is substantially flush with the auxiliary electrodes G'_{2R} and G'_{2B} disposed on both sides of the projection.

With such arrangement, the side beam cutoff voltages are respectively dependent upon the potential relationship among the cathode K_R , the first grid G_1 and the auxiliary electrode G'_{2R} and the potential relationship among the cathode K_B , the first grid G_1 and the auxiliary electrodes G'_{2B} . The central beam cutoff voltage depends upon the potential relationship among the cathode K_G , the first grid G_1 and the second grid G_2 . Accordingly, by suitable selection of the potentials V_1 , V_3 and V_{g2} of the auxiliary electrodes G'_{2R} and G'_{2B} and the second grid G_2 , the cutoff voltages of the respective beams B_R , B_G and B_B can be made equal to one another, thereby to render uniform the beam modulation characteristics for the three beams.

While the present invention has been described as being applied to an electron gun in which the first grid G_1 is common to the cathodes K_R , K_G and K_B , the invention is also applicable to electron guns, such as are shown in FIGS. 4 and 5, in which

the first grid G_1 is divided into individual grids respectively corresponding to the cathodes K_R , K_G and K_B . In FIGS. 4 and 5, the respective cathodes and first grids are angularly displaced from each other so as to radiate from, and be equally spaced from the optical center of the main electron lens.

In the examples illustrated in FIGS. 3, 4 and 5, no auxiliary electrode is provided for the central beam B_G and the second grid G_2 is used to perform the function of the auxiliary electrode for the central beam B_G in addition to performing the usual function of the second grid for the side beams B_R and B_B . However, the omission of the auxiliary electrode need not be limited specifically to the central beam but, instead, the auxiliary electrode for any one of the beams may be omitted.

When the plural-beam electron gun has the auxiliary electrodes for rendering the beam cutoff voltages and the beam modulation characteristics uniform interposed between the first grid G_1 and the second grid G_2 for providing an axially symmetrical potential distribution, and the potentials of the auxiliary electrodes and the second grid are different from each other, an electron lens is formed between the second grid and the auxiliary electrodes by the potential relationship therebetween which exerts an influence upon the angles of divergence of the beams from the auxiliary electrodes.

The potential relationship between the second grid and the auxiliary electrodes may influence the divergent angles of the beams in two different ways according to the arrangement and construction of the auxiliary electrodes. When the auxiliary electrode G'_2 interposed between the first and second grids G_1 and G_2 is placed near the former, as depicted in FIG. 6, the potential relationship between electrode G'_2 and grid G_2 will have one influence, and when the auxiliary electrode G'_2 interposed between the first and second grids G_1 and G_2 is located further from grid G_1 , the potential relationship between electrode G'_2 and grid G_2 will have the opposite influence, as shown on FIG. 7.

In the case of FIG. 6, when the potential V_1 of the auxiliary electrode G'_2 is lower than the potential V_{g2} of the second grid G_2 , the beams diverge at an angle θ_1 greater than the angle θ_0 at which the beams diverge from $V_{g2} = V_1$, as shown on FIG. 6A. If the divergent angle of the beams is thus made great, a wide area of the main electron lens L is used for beam focusing which is likely to be affected by aberration.

On the other hand, when the potential V_1 of the auxiliary electrode G'_2 is higher than the potential V_{g2} of the second grid G_2 , the beams diverge at an angle θ_2 smaller than the angle θ_0 in the case of $V_{g2} = V_1$, as shown on FIG. 6B. When the divergent angle of the beams is thus made small, the beams pass through only a relatively small central area of the main electron lens L , near the optical axis of the lens so as to be focused with minimal aberration and thereby permit the bright spot formed on the screen to be reduced in diameter. Accordingly, in the case where the auxiliary electrode G'_2 is located near the first grid G_1 , as shown in FIGS. 6A and 6B, it is preferred that the potential V_1 of the auxiliary electrode G'_2 be higher than the potential V_{g2} of the second grid G_2 in order to improve the focusing characteristics.

In the case of the auxiliary electrode G'_2 being substantially spaced from first grid G_1 , for example, approximately midway between grids G_1 and G_2 , the potential V_1 of the auxiliary electrode G'_2 being lower than the potential V_{g2} of the second grid G_2 , causes the beam to diverge at an angle θ_3 smaller than divergence angle θ_0 that results when $V_1 = V_{g2}$, as illustrated in FIG. 7A.

Conversely, in the event that the potential V_1 of the auxiliary electrode G'_2 is higher than the potential V_{g2} of the second grid G_2 , the divergence angle θ_4 is then greater than the angle θ_0 , as shown in FIG. 7B. Accordingly, in the case where the auxiliary electrode G'_2 is located substantially midway between the first and second grids G_1 and G_2 as depicted in FIGS. 7A and 7B, it is preferred that the potential V_1 of the auxiliary electrode G'_2 be lower than the potential V_{g2} of the second grid G_2 for obtaining optimum beam focusing characteristics.

In the case where the auxiliary electrodes G'_{2R} and G'_{2B} are provided for both side beams and no auxiliary electrode is provided for the central beam, but instead the second grid G_2 is formed to partially project toward the first grid G_1 as depicted in FIGS. 3, 4 and 5, there is the possibility that, when the voltages of the second grid G_2 and the auxiliary electrodes G'_{2R} and G'_{2B} are adjusted for making the respective beam current cutoff voltages uniform, the potential relationship between the second grid G_2 and each of the auxiliary electrodes G'_{2R} and G'_{2B} may not be in accordance with the preferred relationships described above.

Thus, if the attainment of uniform beam current cutoff voltages requires any one of the auxiliary electrodes G'_{2R} and G'_{2B} to be at a potential V_1 greater than the potential V_{g2} of the second grid G_2 , then such auxiliary electrode is disposed near to the first grid G_1 for attaining optimum focusing characteristics with respect to the related beam, for example, as in FIG. 6B. On the other hand, if the attainment of uniform beam current cutoff voltages requires any one of the auxiliary electrodes G'_{2R} and G'_{2B} to be at a potential less than the potential V_{g2} of the second grid G_2 , then such auxiliary electrode is disposed at a relatively large distance from first grid G_1 , for example, midway between grids G_1 and G_2 , for attaining optimum focusing characteristics with respect to the related beam, as shown on FIG. 7A.

Turning now to FIGS. 8 and 9, it will be seen that such views illustrate further examples of this invention, in which individual first grids G_{1R} , G_{1G} and G_{1B} are respectively provided for the cathodes K_R , K_G and K_B and auxiliary electrodes G'_{2R} and G'_{2B} are respectively interposed between the first grids G_{1R} and G_{1B} and the second grid G_2 .

In the electron gun of FIG. 8, when the potentials V_1 of the auxiliary electrodes G'_{2R} and G'_{2B} are higher than the potential V_{g2} of the second grid G_2 , the divergence angle of each of the side beams is made smaller than that when the potentials V_1 and V_{g2} are equal to each other, specifically by positioning the auxiliary electrodes G'_{2R} and G'_{2B} between the first and second grids G_1 and G_2 at locations near to first grid G_1 , as previously described. In such case distance D_1 between the central cathode K_G and the first grid G_{1G} is made shorter than the corresponding distances between the side cathodes K_R and K_B and their respective first grids G_{1R} and G_{1B} or the aperture g_{1G} of the central first grid G_{1G} is formed with a diameter greater than the diameters of apertures g_{1R} and g_{1B} of the side first grids G_{1R} and G_{1B} . In this case, the relative decrease in the distance D_1 , or the relative increase in the size of aperture g_{1G} , serves to increase the central beam cutoff voltage. Thus, even though the potentials of auxiliary electrodes G'_{2R} and G'_{2B} are greater than the potential of second grid G_2 and this relationship would otherwise cause the side beam cutoff voltages to be greater than the center beam cutoff voltage, relatively decreasing the distance D_1 , or relatively increasing the size of aperture g_{1G} , can serve to equalize the beam cutoff voltages for the three beams.

On the other hand, in the electron gun of the described construction, when the potentials V_1 of the auxiliary electrodes G'_{2R} and G'_{2B} are made lower than the potential V_{g2} of the second grid G_2 , the divergence angle of each of the side beams is made smaller than that when the potentials V_1 and V_{g2} are equal to each other, by disposing the auxiliary electrodes G'_{2R} and G'_{2B} substantially midway between the first and second grids G_1 and G_2 , as described above, and further in that case the distance D_2 between the central cathode K_G and the first grid G_{1G} is made longer than the corresponding distances between the side cathodes K_R and K_B and their respective first grids G_{1R} and G_{1B} as depicted in FIG. 9, or the aperture g_{1G} of the central first grid G_{1G} is made smaller than the apertures g_{1R} and g_{1B} of the side first grids G_{1R} and G_{1B} . In this case, either the relative increase in the distance D_2 , or the relative decrease in the size of the aperture g_{1G} , serves to decrease the central beam cutoff voltage. Thus, even though the potentials of auxiliary electrodes G'_{2R} and G'_{2B} are adjusted to be smaller than the potential of second grid G_2 , and this relationship

would otherwise cause the side beam cutoff voltages to be less than the center beam cutoff voltage, relatively increasing the distance D_2 , or relatively decreasing the size of aperture g_{1G} , can serve to bring down the center beam cutoff voltage to be equal to the adjusted side beam cutoff voltages.

Thus, in accordance with this invention, as has been described in the foregoing, it is possible to make the respective beam cutoff voltages equal and hence render the beam modulation characteristics uniform without imparting any distortion to the pre-focusing lens by the auxiliary electrodes and, at the same time, the divergence angles of the beams can be held small to thereby provide for improved beam focusing characteristics. This invention is of particular utility when employed in large size cathode ray tubes of the Trinitron (Registered Trademark) type.

Although illustrative embodiments of the invention have been described in detail herein with reference to the drawings, it is to be understood that the invention is not limited to those precise embodiments, and that various changes and modifications may be effected therein by one skilled in the art without departing from the scope or spirit of the invention.

What is claimed is:

1. A cathode ray tube comprising:
  - A phosphor screen;
  - Beam producing means to form a plurality of separately modulatable electron beams to impinge on said screen after intersecting each other at a location in the tube between said beam producing means and said screen, said beam producing means comprising:
    1. cathode means emitting the electrons to form said beams, and
    2. a grid electrode assembly for controlling the electron beams, said grid electrode assembly comprising:
      - a first grid electrode,
      - b. a second grid electrode arranged to act on each of said beams, and
      - c. auxiliary electrode means arranged between said first and second grid electrodes in the path of at least one of said beams and having a voltage applied thereto which is related to the potentials of said first and second grid electrodes for achieving independent control of the modulating conditions for said beams; and
  - C. Electron lens means common to all of said beams and comprising main focusing lens means positioned to dispose the optical center thereof substantially at said location in the tube, said lens means comprising a plurality of electrodes arranged between said grid electrode assembly and said screen.
2. A cathode ray tube according to claim 1, in which said auxiliary electrode means is provided for each of said beams.
3. A cathode ray tube according to claim 1, in which there are three of said electron beams directed by said beam producing means in a common plane, said auxiliary electrode means includes an auxiliary electrode for each of said three beams, and the voltage applied to the auxiliary electrode for the central one of said three beams is the same as the potential of said second grid electrode.
4. A cathode ray tube according to claim 1, in which said plurality of electron beams consists of a central beam and two side beams directed by said beam producing means in a common plane, and said auxiliary electrode means consists of an auxiliary electrode only for each of said side beams.
5. A cathode ray tube according to claim 4, in which said second grid electrode has a central projection extending toward said first grid electrode through which said central beam passes.
6. A cathode ray tube according to claim 4, in which there are independent cathode means and an independent first grid electrode for each of said beams, said voltage applied to each auxiliary electrode is different from said potential of said second grid electrode, and said cathode means and first grid electrode for said central beam are arranged relative to each

other to provide said central beam with a cutoff voltage that is equal to the cutoff voltage for each of said side beams.

7. A cathode ray tube according to claim 6, in which said voltage applied to each said auxiliary electrode is greater than said potential of said second grid electrode.

8. A cathode ray tube according to claim 7, in which said cathode means for said central beam is disposed closer to the respective first grid electrode than are the cathode means and said first grid electrodes for the side beams.

9. A cathode ray tube according to claim 7, in which said first grid electrodes have apertures for the passage of the respective beams therethrough, and the aperture of said first grid electrode for said central beam is of greater size than the apertures of the first grid electrodes for the side beams.

10. A cathode ray tube according to claim 7, in which said auxiliary electrodes are disposed relatively near to the respective first grid electrodes.

11. A cathode ray tube according to claim 6, in which said voltage applied to each said auxiliary electrode is less than said potential of said second grid electrode.

12. A cathode ray tube according to claim 11, in which said auxiliary electrodes are disposed approximately midway between the respective first grid electrodes and said second grid electrode.

13. A cathode ray tube according to claim 11, in which said cathode means for said central beam is disposed further from the respective first grid electrode than are the cathode means and said first grid electrodes for the side beams.

14. A cathode ray tube according to claim 11, in which said first grid electrodes have apertures for the passage of the respective beams therethrough, and the aperture of said first grid electrode for said central beam is of smaller size than the apertures of the first grid electrodes for the side beams.
